UNITED STATES PATENT OFFICE.

EUGENE JENOI AND SANDOR NAGY, OF THORPE, WEST VIRGINIA; SAID JENOI
ASSIGNOR OF ONE-HALF OF THE WHOLE TO STEVE KRUCHIO, ROZALIA MARY
SZABO, AND SARAH KRUCHIO, ALL OF UNIONTOWN, PENNSYLVANIA.

GARMENT-HANGER.

1,113,640.

Specification of Letters Patent. Patented Oct. 13, 1914.

Application filed July 3, 1913. Serial No. 777,205.

To all whom it may concern:

Be it known that we, EUGENE JENOI and SANDOR NAGY, subjects of the King of Hungary, residing at Thorpe, in the county of McDowell and State of West Virginia, have invented certain new and useful Improvements in Garment-Hangers, of which the following is a specification, reference being had therein to the accompanying drawing.

10 This invention relates to garment hangers, and has for its object to provide a hanger, in the manner as hereinafter set forth, in the form of a chain consisting of a plurality of interengaging and separable links whereby 15 the length of the hanger can be increased or diminished when occasion so requires.

A further object of the invention is to provide a coat hanger in the form of a chain having each of its end links capable of being 20 detachably connected to the garment for the purpose of securing a hanger in position.

Further objects of the invention are to provide a coat hanger, which is comparatively simple in its construction and arrangement, 25 strong, durable, efficient in its use, conveniently connected to the garment, and comparatively inexpensive to manufacture.

With the foregoing and other objects in view, the invention consists of a novel construction, combination and arrangement of parts as hereinafter more specifically described and illustrated in the accompanying drawing wherein is shown an embodiment of the invention, but it is to be understood that 35 changes, variations and modifications can be resorted to which fall within the scope of the claims hereunto appended.

In describing the invention in detail, reference is had to the accompanying drawing 40 wherein like reference characters denote corresponding parts throughout the several views and in which:

Figure 1 is an elevation of a garment hanger in accordance with this invention 45 showing the adaptation thereof in connection with a garment, Fig. 2 is a longitudinal sectional plan of a hanger showing the same attached to a garment, Figs. 3, 4 and 5 are perspective views of the links forming the 50 hanger, Fig. 6 is a plan of the blank from which an end link of the hanger is constructed, and Fig. 7 is a plan of the blank from which an intermediate link of the hanger is constructed.

A hanger in accordance with this invention includes a pair of end links 8, 9 and a plurality of intermediate links 10. The end and intermediate links interengage with each other and can be separated from each other when occasion so requires. The end link 8 comprises a body portion formed of a plate 11 flanged at each end as at 12 and at each side as at 13. The flange 13 is extended and bent upon itself to form a hook 14 and said flange 13 is slotted as at 15 to increase 60 the length of the shank of the hook. Projecting from the free edge of the plate 11 are pointed connecting members 16, 17 having their outer portions offset with respect to their inner portions. The members 16, 17 70 are adapted to pierce the lining 18 of the garment and extend between said lining and the cloth 19 of the garment.

When the link 8 is connected to the garment, the member 17 is bent to extend in an 75 opposite direction with respect to the member 16 which is clearly shown in Fig. 2. The end link 9 consists of a body portion including a plate 18 having a flange 19 at each end and a flange 20 at one side. The flange 20 is formed with a rectangular slot 21 for the purpose to be presently referred to. Projecting from the free edge of the plate 18^a 80 are connecting members 22, 23, the outer portions thereof being offset with respect to the inner portions. When the link 9 is connected to the garment, the member 23 extends in an opposite direction with respect to the member 22 as clearly shown in Fig. 2.

Each intermediate link is formed from a 90 rectangular plate 24 having the flanges 25, 26 at the ends thereof and the flanges 27, 28 at the sides thereof. The flange 26 is formed with an extension, bent upon itself to provide a hook 29 and to increase the length of 95 the shank of the hook 29 the flange 26 is slotted, as at 30. The flange 25 is formed with a rectangular slot 31 for the purpose to be presently referred to.

The reference character 32 denotes the 100 blank from which the end link 8 is formed and the reference character 33 denotes the blank from which an intermediate link is formed.

The intermediate links 10 are detachably 105 connected to each other by the hook 29 of one link extending through the slot 31 to an adjacent link and the bill of the hook abut-

ting against the flange 25, as clearly shown in Fig. 2. The end link 8 is connected to an intermediate link by the hook 14 extending through the slot 31 in the flange 25 and the 5 abutting of the bill of the hook 14 against the inner face of that flange through which the hook extends. The intermediate link is connected to the end link 9 by a hook 29 extending through a slot 21 and the bill of the hook 29 engaging the inner face of the flange 20.

The hooks 29 are resilient so that they can be compressed to enable the intermediate links being disconnected from each other. 15 and also from the end link 9. The hook 14 is resilient to enable the same to disconnect from the intermediate link.

By detachably connecting the links together, the length of the hanger can be increased or diminished when occasion so requires.

What we claim is:—

A coat hanger formed of a chain comprising a pair of outer links and a plurality of

intermediate links, each of said outer links 25 consisting of a body portion provided with flanges and further having bendable connecting members for detachably connecting said links to the garment, the body portion of one of said outer links being slotted and 30 the body portion of the other of said outer links having projecting therefrom an extension having a resilient hook, each of said intermediate links consisting of a plate provided with a rectangular flange, one end of 35 said flange being slotted and the other end of said flange having projecting therefrom an extension having a resilient hook, said slots and extensions of said links providing means for detachably connecting the links 40 together.

In testimony whereof we affix our signatures in the presence of two witnesses.

EUGENE JENOI.
SANDOR NAGY.
